UNITED STATES PATENT OFFICE

145,335

DESIGN FOR A SET OF CHESSMEN

Arthur R. Scott, Kansas City, Mo.

Application October 15, 1945, Serial No. 122,839

Term of patent 14 years

(Cl. D34—5)

To all whom it may concern:

Be it known that I, Arthur R. Scott, a citizen of the United States, residing at Kansas City, in the county of Jackson and State of Missouri, have invented a new, original, and ornamental Design for a Set of Chessmen, of which the following is a specification, reference being had to the accompanying drawing, forming a part thereof.

Fig. 1 is a side elevational view of the set of

chessmen comprising the queen, king, bishop, knight, rook and pawn, showing my new design.

Fig. 2 is a front elevational view thereof; and Fig. 3 is a top plan view thereof.

I claim:

The ornamental design for a set of chessmen, as shown.

ARTHUR R. SCOTT.
